PIPE COATING APPARATUS

Albert G. Perkins, Warsaw, and Charles E. Perkins, Buffalo, N. Y., assignors to Centriline Corporation, a corporation of Delaware

Application September 9, 1937, Serial No. 163,044

7 Claims. (Cl. 91—45)

This invention relates to an apparatus which has been designed more particularly for applying a protective coating or lining to the inner walls of pipe lines and conduits, such as water and sewer pipe lines and tunnels.

One of its objects is the provision of an efficient apparatus of this character which is designed and constructed to travel through the pipe line and as it does so automatically apply to the pipe-wall an even and durable coating of protective material, such as cement mortar.

Another object of the invention is to provide simple and effective means for conveying the coating material to its point of discharge, and for thoroughly and effectually agitating and breaking up the material just prior to its discharge, in combination with means for delivering or discharging the material by air pressure and impacting it against the pipe wall.

Another object of the invention is the provision of an efficient trowel mechanism for uniformly smoothing down the material after it is applied to the pipe-wall.

Other features of the invention reside in the construction and arrangement of parts herein-after described and particularly pointed out in the appended claims.

In the accompanying drawings:

Figure 1 is a side elevation of my improved coating apparatus, shown within a pipe line for treating the interior wall thereof with a protective coating. Figure 2 is a front view of the troweling mechanism arranged within the pipe. Figure 3 is a front view of the distributing disk or conveyor taken in the plane of line 3—3, Figure 1, for directing the coating material outwardly from the feed pipe to the spraying head of the apparatus. Figure 4 is an enlarged fragmentary longitudinal section taken in the plane of line 4—4, Figure 1. Figure 5 is a cross section taken on line 5—5, Figure 4. Figure 6 is a fragmentary transverse section taken on line 6—6, Figure 5. Figure 7 is a vertical section taken on line 7—7, Figure 6.

Similar characters of reference indicate corresponding parts throughout the several views.

While my apparatus may be employed for coating different kinds of work, it has been primarily designed for treating the inner walls of steel pipe lines with a protective coating, such as for example as a plastic-like material as cement mortar. To this end, the apparatus consists generally of a carriage which is adapted to be propelled through the pipe line and which carries the working parts of the apparatus, such

working parts comprising a feed nozzle, a hopper for receiving the plastic material means within said hopper for mixing and agitating the material, means for conveying the material to a second hopper where it is further mixed and thence to a dispensing or discharge head where it is discharged by air pressure onto the pipe wall and means for troweling or smoothing down the material after it has been applied to the pipe wall.

Referring now to the drawings, 10 indicates a section of the steel pipe line through which my apparatus is designed to travel for treating or coating the inner wall thereof with a covering of concrete or like plaster material. The carriage of the apparatus, which carries its working parts, may be of any appropriate construction, that shown in the drawings by way of example, consisting of a structural steel frame 11 provided at one end with traction or supporting wheels 12 mounted on a transverse axle 13 journaled in said frame and provided at its opposite end with a steering wheel or caster 14 mounted on a swiveling fork 15 suitably supported on the frame 11. Motion is transmitted to the traction wheels from an electric motor 16 mounted on the carriage frame, the drive from the motor consisting, for example, of a train of gears 17, a speed transmission 18, a horizontal shaft 19 having a worm 20 thereon meshing with a worm wheel 21 mounted on a transverse shaft 22. Connecting the shaft 22 and axle 13 is a chain and sprocket drive 23. The speed transmission 18 is preferably employed for the purpose of propelling the carriage through the pipe at different speeds and thereby govern the thickness of the coating material applied to the pipe wall. For the purpose of description, viewing Figure 1 of the drawings; the right hand end is the front end and the left hand end is the rear end of the machine.

Disposed at the front end of the machine and mounted on wheels 24 is a hopper or container 25 into which the material is fed from a supply nozzle or conduit 26, the latter including feed pipes 26^a and 26^b for the cement and water, respectively. This hopper 25 terminates at its rear end in a conduit or passage 27 and extending axially through these parts is an agitating or mixing unit including an actuating shaft 28 which is journaled at one end in the end wall of the hopper and at its other in appropriate bearings. Applied to the front portion of this shaft are a series of paddles 29 which act to mix the elements of the material to the proper con-

sistency and disposed in the passage 27 and mounted on the rear portion of said shaft is a screw conveyor 31 which forces the material through the passage 27.

The shaft 29, upon which the paddles 30 and screw conveyor 31 are mounted, is driven at a comparatively slow speed by the motor 16, as for example, from a gear train 32 to a gear reducer 33 connected by a universal joint 34 with a shaft 35 extending lengthwise of the machine having a sprocket 36 connected by a chain 37 with a sprocket 38 mounted on the front end of the shaft 29.

From the discharge end of the hopper 25, the material passes into a second hopper or container 39 where it is further agitated by a second series of paddles 40 mounted on a tubular shaft 41 which is journaled at one end in the end wall of the hopper and at the other end in a bearing 42 at the rear end of the machine. The mixed material is conveyed from this second hopper through a feed conduit 43 by a screw conveyor 44 also mounted on the shaft 41. To prevent undue pressure being exerted by the material as it is propelled through the feed conduit by the screw conveyor 44, I provide the blades of the conveyor 44 with a notch or relief 45.

The tubular shaft 41, upon which the paddles 40 and conveyor 44 are mounted, is driven also at a slow speed by a gear train 46 connected to the speed reducer 33.

The means for dispensing or discharging the coating material by air pressure and impacting it onto the pipe wall is preferably constructed as follows:

At its rear or discharge end the feed conduit 43 has a substantially cylindrical chamber 47 of somewhat larger diameter than said conduit and consisting of axially-spaced, dished plates or disks 48 providing an annular peripheral discharge 49 for the emission of the material therefrom onto the pipe-wall. Between the disks 48 in concentric spaced relation thereto and in facial relation to the conduit 43 is a revolving head or conveyor 50 mounted on the shaft 41 to turn therewith and having a plurality of spiral blades 51 on its face for directing the plastic material from the center of the chamber 47 to the outer or peripheral portion thereof from where it is sprayed onto the pipe-wall by a source of air pressure. The air pressure is connected from a suitable source of supply, not shown, to an annular pipe 52 applied to one of the discs 48 and having a plurality of radial jets 53 projecting therefrom into the peripheral portion of the chamber 47 in the manner shown in Figures 4-7 inclusive, and having their discharge ends facing outwardly for directing streams of air against the material to force it in an annular, spray-like fashion onto the pipe wall. In order to effect a uniform distribution of air to the several jets, the pipe preferably converges from its medial inlet to the opposite ends thereof, as seen in Figure 5.

For the purpose of uniformly smoothing down the coating material after it has been applied to the pipe-wall I provide a troweling mechanism which is disposed immediately to the rear of the dispensing head. In its preferred construction, this troweling mechanism consists of two annular rows of trowels 54, 55, the rear trowels 54 being independently mounted on comparatively long flexible rods 56 in over-

lapping relation with the front trowels 55 which are mounted independently on shorter flexible rods 57. These rods are adapted to be bowed more or less when operatively engaged with the pipe-wall and are arranged in spaced radial relation to simulate the shape of a bell and are attached at their inner ends at 58 to a hub 59 formed on the rear chamber-plate 47. Connected to the rods 56 and 57 intermediate their ends are tie rods 60 fulcrumed to companion collars 61 fixed to a horizontal push-rod 62 slidably mounted in the tubular shaft 41 and threaded at its front end for actuation by a nut or hand wheel 63, which when turned in one direction or the other, tends to bow the rods to govern the tension of the trowels on the cement mortar and to adapt them to varying cross-sectional areas and contours of the pipe. By this construction, as the coating machine travels through the pipe line, the trowels exert a uniform pressure on the applied coating and evenly smooth it down throughout its entire circumference. As shown, the trowels are provided with a plurality of slits 54a to render them flexible circumferentially of the pipe.

Mounted on the discharge end of the hopper 25 is an indicator for indicating to the operator the degree of consistency of the coating material, this indicator consisting of a swinging valve or damper 64 extending part-way across the hopper-passage 27 and having an arm 65 extending therefrom connected by a link 66 with a movable pointer 67 arranged to traverse an indicator scale 68 properly calibrated to register the consistency of the material passing through the hopper. Should the material be of a stiff consistency the valve 64 will be swung forwardly and register that consistency on the indicator; should the material be comparatively thin, the valve will be moved only slightly or not be affected at all and this will be indicated at the scale, a spring 69 bearing against the arm 65 tending to hold the valve in a maximum open position. If desired, the arm 65 may be connected by a link 70 with the valve 71 of the water pipe 26b of the feed nozzle 26, so that in response to the movements of such arm the water supply is increased or decreased in accordance with the consistency of the material passing through the hopper and thereby the water supply is automatically regulated to provide for the proper consistency of the mix.

If desired, one of the walls 48 of the chamber 47 may be provided with vents or ports 72 preferably disposed immediately below the jets 53 and through which air may be drawn into such chamber for increasing the spraying action of the mortar onto the pipe-wall.

We claim as our invention:

1. An apparatus for lining pipe walls, comprising a feed conduit for the coating material having an axial discharge terminating in an enlarged chamber having a peripheral discharge, a revolving head arranged in said chamber in operative facial relation to the conduit-discharge and having means thereon for directing the coating material uniformly toward said chamber-discharge, and means interposed between the periphery of said revolving head and said chamber-discharge for introducing air under pressure against the coating material and directing it outwardly against the pipe-wall.

2. An apparatus for lining pipe walls, com-

prising a feed conduit for the coating material having an axial discharge terminating in an enlarged chamber having a peripheral discharge, a revolving head arranged in said chamber in operative facial relation to the conduit-discharge and having spiral like blades thereon radiating from the center of the head and terminating at their outer ends short of its peripheral-discharge; for directing and forcing the coating material from the center of said chamber outwardly toward said peripheral chamber-discharge, and fluid pressure means applied to said head and having outlets opening into the same between its periphery and the opposing ends of said blades for forcing the material outwardly through the peripheral-discharge onto the pipe-wall.

3. An apparatus for lining pipe walls, comprising a feed conduit for the coating material having an axial discharge terminating in an enlarged chamber having a peripheral discharge, a revolving head arranged in said chamber in operative facial relation to the conduit-discharge and having means thereon for directing the coating material uniformly toward said chamber-discharge, and a plurality of air jets arranged in an annular row about said chamber short of its peripheral discharge for directing the coating material outwardly in spray-like fashion against the pipe-wall.

4. An apparatus for lining pipe walls, comprising a feed conduit for the coating material having an axial discharge terminating in an enlarged chamber having a peripheral discharge, a revolving head arranged in said chamber in operative facial relation to the conduit-discharge and having means thereon for directing the coating material uniformly toward said chamber-discharge, a plurality of air jets arranged in an annular row about said chamber short of its peripheral discharge for directing the coating material outwardly in spray-like fashion against the pipe-wall, and an air supply pipe for said jets extending about said chamber and decreasing in diameter from its medial inlet to the diametrically opposite ends thereof.

5. An apparatus for lining pipe walls, comprising a structure adapted to travel through the pipe, a container for receiving a supply of coating material and having a conduit in communication therewith, means for positively and continuously feeding the material through said conduit, a second container for receiving the supply of coating material from said first-named container and having a feed conduit in communication therewith, means for positively and continuously feeding the material through said feed conduit toward its discharge end, an annular chamber having a peripheral discharge and in communication relation with said last-named feed conduit, a revolving conveyor means within said chamber for conducting the material toward its peripheral discharge, and pressure means for delivering the material through said discharge onto the pipe-wall.
6. An apparatus for lining pipe walls, comprising a hopper for the coating material including a feed conduit, means in said conduit actuated by the material flowing therethrough; the degree of movement of said means being determined by the consistency of the material, a consistency indicator operatively connected to said material-actuated means, and means for applying said material to the pipe wall.
7. An apparatus for lining pipe walls, comprising a feed conduit for the coating material having an axial discharge terminating in an enlarged chamber having a peripheral discharge, a revolving head arranged in said chamber in operative facial relation to the conduit-discharge and having means thereon for directing the coating material uniformly toward said chamber-discharge, and a plurality of air jets arranged in an annular row about said chamber short of its peripheral discharge for directing the coating material outwardly in spray-like fashion against the pipe-wall, said chamber having air ports in one of its walls in proximity to said air jets.
